UNITED STATES PATENT OFFICE.

GEORGE ARTHUR KEANE, OF NEW YORK, N. Y.

SECTIONAL TABLE.

1,410,476.

Specification of Letters Patent. Patented Mar. 21, 1922.

Application filed November 29, 1920. Serial No. 426,983.

To all whom it may concern:

Be it known that I, GEORGE A. KEANE, a citizen of the United States, residing at New York, in the county of New York and State 5 of New York, have invented certain new and useful Improvements in Sectional Tables, of which the following is a specification.

This invention involves certain aids to self-culture for bringing the human body 10 back to its normal condition, and to this end the purpose of the aids are to induce in a person proper breathing and posture, together with the power over the body and nerves to relax and devitalize so that the 15 blood may circulate freely through every part of the body.

The discovery and invention has many uses and is applicable to building up many parts and phases of the human body and 20 system, among which may be stated that it will relieve tension in the nerves, muscles, veins, arteries, etc., and will so synchronize the movement of the blood that any weak or over-strained part will be built up, strengthened 25 or rehabilitated. By causing the unobstructed flow of blood through the entire body, not only will its various parts be built up and readjusted as they should be, but it will eliminate poisons and other accumulations 30 which ordinarily are not promptly expelled by the body, and with this elimination and readjusting the person will not only feel much better, but he will be able to think, concentrate and use his will or mind 35 to better advantage. With this power to concentrate, the person will soon be able to control any particular part of his body which may be inefficient, over-strained or aching, and by his thoughts can cause the 40 blood to surge through the veins and arteries in the subnormal part whereby the congestion or other cause of the discomfiture is removed.

With the invention and discovery it is possible 45 to develop great elasticity, balance, equilibrium, and coordination of the body, which is practically impossible to obtain without these self-culture aids.

To the end, therefore, of relaxing the entire body, I have devised a means upon 50 which a student may lie and rock any part of his body independently of the rest. The means may be best described by saying that they are a table made in sections, one section 55 for the head, one for the shoulders, one for the hips and one for the feet, with each

of these sections rockable independently of the other. With a person lying on the table, the several sections are gently rocked, alternately and together, which movements 60 completely devitalizes and relaxes the body, whereby the blood is caused to circulate freely in every part and organ which will stimulate and greatly benefit the person so treated. 65

I have illustrated one embodiment of such a table, but it is to be taken in an illustrative sense and not a limiting one, for that phase of the invention is capable of a number of different embodiments. 70

In the illustrations,

Figure 1 is a perspective view of my rocking table;

Figure 2 is a side elevation thereof with a person thereon; 75

Figure 3 is a plan view of the table;

Figure 4 is a sectional view taken along the lines 4-4 in Figure 2;

Figure 5 is an elevation of the foot of the table; 80

Figure 6 is a perspective view of a detail;

Figure 7 shows the table nested;

Figure 8 shows an adjustable feature of

the table, and

Figure 9 shows how the supporting board 85 can be folded.

Figs. 10 and 11 show details of the table.

In the drawings, numeral 11 indicates a supporting board made into sections 12, 13, 14 and 15 hinged together at 16, 17 and 18, 90 so that it may be folded up as shown in Figure 9. This board is provided with a multiplicity of grooves 19 for a purpose herein-after described. Supported on the board 11 are a number of sections of a table adapted 95 to support a person. There is a section 20 for the head, a section 21 for the shoulders, a section 22 for the hips, and a section 23 for the feet. These sections are each provided with two rockers 24 and 25, which rockers 100 are adapted to rock the grooves 19 of the board 11. These sections of the table are adapted to be rocked independently of the other sections. In order that one section may be rocked while the others are main- 105 tained stationary, means are provided for locking adjacent sections together and these means may constitute a slidable plate 26 longitudinally slidably supported from one rocker section and provided with a slotted 110 end 27 adapted to engage a pin 28 on an adjacent rocker section to prevent the rocking

of the adjacent section with respect to the plate carrying section. The plate only needs to be slid longitudinally to lock or unlock the sections. To prevent rocking of the sections either before or after locking, I provide several legs 29 hinged at 30 which may be let down, as shown in Figure 2, to prevent rocking, or may be moved upwardly about the hinge 30 to permit rocking. These legs 10 are held in the desired position by friction. To assist rocking of the sections I may provide a plurality of springs 31 and 32 for each section which lie between the section and its support.

15 It may be desirable to adjust certain parts of the body upon the table so I may use a small bag 33 filled with some suitable substance and this bag can be readily moved about upon the table to adjust the body as desired. To adjust the feet I provide two foot plates 34 and 35, slotted at 36 and adjustably held in position upon the foot section 23 by means of thumb screws 37. These foot plates 34 and 35 are equipped with stirrups 38. In order to adjust the device for a child, there are sufficient grooves 19 in the supporting board 11 so that one of the sections, such as 22, could be omitted (see Figure 8) and only the head section, the shoulder section and the foot section used. This gives great adjustability for the different students using the device.

In operation the student will lie upon the table and the sections 21, 22 and 23 will be 35 locked together by the locking devices 26, and the legs 29 will be let down to prevent rocking. This will permit the rocking of the head section 20 only. The student moves his head slightly, which rocks the head section back and forth, and this rocking completely relaxes and eliminates all tension 40 from the body, whereby all muscular constriction of the blood vessels is removed. After a complete relaxation of the neck, the shoulder section 21 is similarly rocked 45 whereby complete relaxation and devitalization of the shoulders and upper body take place. Next the hip section is similarly rocked with their consequent devitalization and finally the feet are rocked to relax the ankles and the entire feet. When thus thoroughly relaxed and devitalized, the blood flow 50 is not only accentuated, but passes to every part of the body, rebuilding as it goes, and bringing back to the lungs impurities it has 55 collected and in the lungs it meets air sufficient to remove from the blood and carry out of the body the various accumulations collected thereby.

60 The rocking sectional table is important as such but it may be used either on the supporting board or base 11 as described, but any device for keeping the rocking sections in alignment may be substituted for the board. One substitute form I prefer and

that is wherein I use a rod or shaft over which the sections rock. Such a device is shown in Figures 10 and 11 in which 15^a represents any floor on which is deposited or laid down the shaft 39 extending the full 70 length of the table. 40 and 41 represent collars and ridges upon the shaft forming guides between which the rockers 24 and 25 can rock. An aperture is provided in each rocker so it can straddle the shaft. This 75 shaft, if desired, can be jointed and a plurality of the guides 40 and 41 can be provided as in the case of the grooves 19 and the board 11 to make the table adjustable. Also straps can be used in connection with 80 the table if desired to strap that part of the body to its corresponding table section.

The rocking table is effective in inducing in the student the control of any part of the body, by the mind, or in other words, better co-ordination. It can thus be seen that the invention and discovery is based solely on putting the student in a position to improve and help himself so that the expressive title hereof has been carefully chosen. 90

What I claim is:

1. A method of health improvement which consists in imparting to the human body in a recumbent position a slight lateral rocking movement, successively and independently, 95 of the head, shoulders, hips and feet.
2. A method of health improvement which consists in imparting to the human body in a recumbent position a slight lateral rocking movement, non-synchronously, of the 100 head, shoulders, hips and feet.
3. A sectional rocking table with a separate independently rockable section each for the head, shoulders, hips and feet of a person resting on the table. 105
4. In a table, a head-rocking section, a shoulder rocking section, a thigh rocking section, a foot rocking section, said sections being independently rockable and means for maintaining said sections in alignment. 110
5. In a table having independently rockable sections, longitudinally movable means for securing desired sections together.
6. In a table having independently rockable sections, slideable means for securing desired sections together. 115
7. In a table having independently rockable sections, pivoted means for maintaining desired sections unrockable.
8. An exercising apparatus having independently rockable sections for the head, shoulders, thighs and feet, normally presenting a surface adapted to support a human body in a recumbent position, and spring means acting to return the sections 120 to normal position when they are rocked.
9. An exercising apparatus having independently rockable sections for the head, shoulders, thighs and feet, normally presenting a surface adapted to support a hu- 130

man body in a recumbent position, a rod about which said members are adapted to swing axially and guiding means on the rod for the members.

5 10. An exercising apparatus having independently rockable sections for the head, shoulders, thighs and feet, normally pre-

senting a surface adapted to support a human body in a recumbent position, a rod about which said members are adapted to 15 swing axially, said members having a cut away portion adapted to fit over the rod.

In testimony whereof I affix my signature.

GEORGE ARTHUR KEANE.
